UNITED STATES PATENT OFFICE

HORACE C. YATES AND FRANK L. HANN, OF MOUNT VERNON, IOWA

ADHESIVE-TAPE DISPENSER

Application filed May 23, 1927. Serial No. 193,641.

This invention relates to the use of adhesive tape in surgery, and more particularly of strips of such adhesive material as ripped from a wide sheet thereof. In surgery, strips of adhesive may range in width from a fraction of an inch to several inches, and it is most convenient, and very much more economical, to tear off a strip of any desired width from a wide sheet than to take it from rolls of a limited number of widths of such material. The wide material is prepared for use by covering the adhesive face with a sheet of gauze, when it may be rolled up without sticking together. To tear down a strip of any desired width is a simple and easy matter if the web of material is held firmly, especially at the end from which the tear is started. This is practically impossible with one hand, and an assistant is not always available. The result is that much of the material gets stuck together, crumpled and rendered useless in the mere act of tearing off the strips required. It is the object of this invention to provide apparatus which will hold the web firmly at both ends while strips are ripped loose.

A further object is to provide for the rolling up and saving of the gauze web as the adhesive is stripped from it.

30 A further object is to provide means for limiting the length of the strip, as desired, and for cutting it free from the parent web.

The invention is fully disclosed in the description and claims following, reference being had to the accompanying drawing, in which:

40 Figure 1 is a front view in perspective of apparatus embodying the invention as in use. Fig. 2 shows the mounting and ratchet mechanism of the upper roller, at the right end in Fig. 1. Fig. 3 shows sectional details of the mounting for the left end of the same roller. Fig. 4 shows detent mechanism for the end of the lower roller at the right in Fig. 1. Fig. 5 shows the opposite end of the same roller, and its enclosing case. Fig. 6 shows the detent mechanism for the tension spring of the lower roller. Fig. 7 is a section of the same in the line 7-7 of Fig. 6. Fig. 8 is a fragmentary view in perspective illustrative of

the adjustable cross-bar limiting the tearing of the strip. Fig. 9 is a longitudinal section of the same, showing the construction of the strip-cutter.

A sheet-metal wall-plate 5 is bent at one end to form a semi-circular trough 6 adapted to hold snugly in place a casing 7, in which is mounted the parent roll of the adhesive material, in a manner to be described presently. The trough forms a little more than a semi-circle, and being somewhat elastic, pinches the casing tightly when forced therein. The other end of the wall-plate is provided with a pair of outstanding lugs 8 to form supports for the upper roller 9. This may be a simple cylinder of wood, with a central hole 9^a at one end to engage a stud 10, which serves as a bearing at this end. The stud is mounted slidably in a flanged sleeve 11, and carries on its reduced shank a coil spring 12 retained outwardly by a cap 13. By means of a terminal knob 14 the stud may be withdrawn to allow the roller to swing outwardly for the attachment and detachment of this end of the web. A groove 9^b in the roller permits the attachment of the web by a neatly fitting rod 15, in a familiar way. One end of the roller is provided with a fixed stud 16 provided with a ratchet 17 held to any desired position by a pawl 18. The lugs 8 have diagonal slots 8^a to form seats for the roller bearings, so that the stress of the lower roller not only draws the web taut, but also draws the web back against the wall-plate. This makes it easier for the operator, with a finger-nail, to lift the upper edge of the adhesive cloth from the gauze, and thereby get a tearing grip on it to rip it downwardly, as shown in Fig. 1.

45 The lower end of the web 19 is wound on the lower roller 20, which is a well-known spring curtain roller slightly modified. Its fixed stud 21 is provided with a ratchet 22 to hold the roller against the stress of the tension spring (not shown) by the engagement of a pawl 23. The stud passes through a central hole in a flanged circular end-cap 24 fitting inside the casing. Through a key-hole slot in the flange projects a stem 25 with a terminal knob 26. The inner end of the

stem connects with the pawl, and between it and a washer-plate 27 is placed a compression coil spring 28 tending to force the pawl to latching position. A part of the stem is cut away at 25^a, to permit the stem to swing over in the slot, when drawn out, and so lock it in disengaged position by the engagement of the shoulder 25^b with the flange of the casing cap. The other end of the roller is of the familiar spring roller type commonly applied to window shades, having a flat-ended stud 29 with which the internal spring is supposed to connect. For the winding of the spring to produce the desired tension on the roller and web, the end-cap 30 of the casing is provided with a socket 31 to fit the flat-ended stud, and to the spindle of the socket is attached a ratchet 32 and knob 33 by means of which the spring is wound. A pawl 34 holds the spring at any desired tension.

A gap is formed in the casing between rolled edges 7^a to permit the web to pass through. The upper end is drawn up against the tension of the spring (or such tension may be applied later) and is fastened to the upper roller. As the gauze is cleared of adhesive material it is rolled up on the upper roller by means of its knob 35. If in the winding off of the adhesive the tension of the web becomes excessive, the same may be relaxed by releasing the pawl 34 and permitting the tension spring to unwind more or less.

It is evident that the apparatus as thus described will hold the web neatly and firmly in position so that strips may be ripped down of any desired width, and as long as may be needed. In the absence of the cross-bar, to be described presently, strips even longer than the base or wall-plate may be drawn out over the rolled edge of the gap in the casing, since the spring tension of the lower roller will allow the web to come out through the gap, and will snap it back to normal position as soon as the strip is severed. In practice, however, the strips need not generally exceed the length of the base-plate, and provision is made for stopping and cutting them off uniformly.

At the sides of the wall-plate are formed channels 36 opening inwardly, by folding and crimping the sides of the sheet metal in a zig-zag shape, as shown at the upper right hand corner of Fig. 1. These channels form guides for a cross-bar 37, which is also a channel and guide, and is formed with a lip 37^a to retain in its channel a cutter-bar 38. At the ends the front flange of the cross-bar is cut away, and to the extended ends are attached flat springs 39. These and the ends of the cross-bar may slide in the channels, the springs supplying the requisite tension to hold the bar at any desired point. Inside the cross-bar channel is mounted slidably a knife-holding channel or cutter-bar 38. Near one end of the bar is pivoted a

short lever 41 held normally in an upwardly inclined position by a spring 42. Near the other end of the bar is pivoted a knife 43, which in practice may be a safety razor blade set in a folded back 44. This connects by a link 45 with the lever, so that downward pressure on the lever elevates the knife to cutting position, as shown in Fig. 1.

The operation of detaching a strip of adhesive material is simple and evident. With a finger the operator peels up at the top of the adherent sheet a strip as wide as desired, and starts the tearing line. Pulling on the strip it is ripped down to the cross-bar, when with the other hand the operator depresses the lever, elevating the knife, and then pulls it across the strip with a clean cut.

The apparatus may be used, back down, on a table, or on the ground when required in the case of out-door accidents, or fields sports. For indoor use it is best mounted on a wall, or a cabinet or closet door by means of suitable screws 46.

Having thus described our invention, we claim:

1. In apparatus for dispensing surgical tape in the form of a web having a backing sheet to be peeled from the web, a roller for the web, a take-up roller for the residual material, supports for said rollers, and a bar disposed between the rollers and across and in front of the adhesive strip, to limit the tear of said strip.

2. In apparatus for dispensing surgical tape in the form of a web having a backing sheet to be peeled from the web, a roller for the web, a take-up roller for the residual material, a support for said rollers, and a bar disposed between the rollers and across and in front of the adhesive strip, and adjustable along said support.

3. In apparatus for dispensing surgical tape in the form of a web having a backing sheet to be peeled from the web, a roller for the web, a take-up roller for the residual material, a support for said rollers, a bar disposed between the rollers and across and in front of the adhesive strip, and a cutter slideable along the cross-bar, to sever the drawn-out strip.

4. In apparatus of the class specified, a roller for the web, a take-up roller for the residual material, a support for said rollers, a cross-bar disposed across the web between the rollers, a collapsible cutter slideable along the cross-bar, and a lever in operative connection with the cutter, and adapted to move the cutter to strip-severing position.

In testimony whereof we affix our signatures.

HORACE C. YATES.
